UNITED STATES PATENT OFFICE.

JOHN SMITH, OF CALDWELL PRAIRIE, WISCONSIN.

CRANK-PLATE FOR BOLSTER-SPRINGS.

SPECIFICATION forming part of Letters Patent No. 287,335, dated October 23, 1883.

Application filed May 9, 1883. (No model.)

To all whom it may concern:

Be it known that I, JOHN SMITH, of Caldwell Prairie, in the county of Racine, and in the State of Wisconsin, have invented certain new and useful Improvements in Crank-Plates for Bolster-Springs; and I do hereby declare that the following is a full, clear, and exact description thereof.

My invention relates to devices for the attachment of bolster-springs in wagons; and it consists in certain peculiarities of construction, as will be particularly set forth hereinafter.

In the drawings, Figure 1 is a perspective view of a wagon-bolster with its springs attached thereto by means of my device, and Fig. 2 is a like view of the said device alone.

A is a wagon-bolster, and B B are standards rising from each end.

C C are the springs, and D D are my crank-plates, the inner ends of which are bifurcated, and have vertical inner flanges, d d, which receive between them the standards B. These plates are cast with a partly-open horizontal socket, d', into which is inserted a round wrought-iron rod, which is then bent into the shape shown, forming a double crank, D'. The ends of the springs C are then slipped over the ends of the crank-rods D', washers d² applied, and then the ends of the crank-rods D' upset. The crank-plates, with their rods and springs attached, can now be slipped down on top of the bolster, the bifurcated ends of the

plates receiving the standards, as already stated.

In my drawings I have only shown so much of a wagon as was necessary to illustrate my invention; and it will be understood that bolsters or bed-plates are clipped to the top of the springs C, to support a wagon-box, or whatever load may be desired to be carried thereby, and that as the weight increases and the springs yield under it they are forced outward, the crank-rods D' turning in their sockets, to accommodate the lengthening of the springs, and enable the load to be thereby carried nearer to the axles.

Having thus described my invention, what I claim as new, and desire to secure by Letters Patent, is—

In combination with a wagon-bolster having uprights or standards at each end, the metallic crank-plates D, cast with partly-open horizontal sockets d', and bifurcated inner ends with vertical inner flanges, d d, adapted to receive between their bearing-surfaces the bolster-standards, and the double-crank rods D' and springs C, substantially as set forth.

In testimony that I claim the foregoing I have hereunto set my hand, on this 17th day of April, 1883, in the presence of two witnesses.

JOHN SMITH.
